(57) **CLAIM**

The ornamental design for a fluid dispensing apparatus, as shown and described.

DESCRIPTION

FIG. 1 is a perspective view of a fluid dispensing apparatus showing my new design;

FIG. 2 is a back elevational view thereof;

FIG. 3 is a front elevational view thereof;

FIG. 4 is a top plan view thereof;

FIG. 5 is a side elevational view thereof;

FIG. 6 is a bottom plan view thereof;

FIG. 7 is a perspective view of a fluid dispensing apparatus with the cap in an open position; and,

FIG. 8 is a side elevational view thereof, with the cap in an open position.
